UNITED STATES PATENT OFFICE.

THOMAS SPENCER MILLER, OF SOUTH ORANGE, AND JOSEPH H. DICKINSON, OF MONTCLAIR,
NEW JERSEY.

CONVEYING APPARATUS.

No. 895,033.

Specification of Letters Patent.

Patented Aug. 4, 1908.

Application filed May 12, 1905. Serial No. 260,187.

To all whom it may concern:

Be it known that we, THOMAS SPENCER MILLER, a citizen of the United States, and a resident of South Orange, in the county of 5 Essex and State of New Jersey, and JOSEPH H. DICKINSON, a citizen of the United States, and a resident of Montclair, county of Essex, and State of New Jersey, have invented certain new and useful Improvements in Con- 10 veying Apparatus, of which the following is a specification.

Our invention relates to an improved conveying apparatus of the type employing a suspended cable as a trackway, and has par- 15 ticular application to improved means for moving, tightening, raising and lowering the cable. In the present instance, we will de- 20 scribe this apparatus as employed in logging operations in which a central tower or sup- port is employed, from which a cable is 25 erected radially, and the logs lying near this cable are hoisted and conveyed to any pre- determined place. As soon as the logs have 30 been cleared from a certain run this cable is dropped, and a second cable is then picked 35 up upon another line extending radially from the central support. Up to the present time, it has been the practice to detach the 40 long portion of the cable from one side of this central support and pick up a second corre- 45 sponding cable; the object in having two cables being to reduce to a minimum the time lost in changing the cable. Hereto- 50 fore, however, it has always been the prac- tice to shift that portion of the cable, or the 55 main cable extension, running from a point near the tree support to the back anchorage for the same, after one of the main cables has 60 been dropped. In the present instance, it is 65 our intention to support the back portion of 70 the cableway in position, in such manner that in shifting from one cable to another we 75 also shift from one independent back anchor- 80 age to a second. It will be noted that if the 85 45 position of the main cable be shifted radially 90 in the direction of the movement of the sun, 95 the position of the back anchorage will have 100 a corresponding movement, always, how- 105 ever, exactly opposite to the main cable, so 50 that in each position of the cable the back- 55 ward anchorage portion shall be approxi- 60 mately in a straight line with the main cable. 65 An important saving of time and labor is

thus effected, permitting the cableway to be 55 in operation more hours per day, and, there- 60 fore, to convey a greater number of loads when compared with the cableways as ordi- 65 narily constructed. As soon as the cable- 70 way is working in one position, the riggers 75 are preparing a back anchorage for the fol- 80 lowing position. Thus, the operation of the 85 cableway is more continuous than hereto- 90 fore.

Our invention consists in the construction, 95 combination and arrangement of parts set 65 forth in and falling within the scope of the 70 appended claims.

In the accompanying drawings, like char- 75 acters of reference indicate like parts in all 80 of the views; and, Figure 1 is a view illus- 85 trating one preferred embodiment of our 90 apparatus. Fig. 2 is a slightly modified 95 form of apparatus, wherein we employ two 100 separate guys in the space of a single guy 105 forming a continuation of the main cable 110 extension, as shown in Fig. 1. Fig. 3 is a 115 top plan view of an engine designed for em- 120 ployment in conjunction with our apparatus; 125 certain parts of the engine being omitted; 130 such view also illustrating the arrangement 135 and construction of drums for operating the 140 anchorage. Fig. 4 is a detail view showing 145 the drum, ratchet and pawl mechanism.

Referring, now, to the accompanying 150 drawings, A represents the head spar tree or 155 support and B indicates as a whole an engine 160 employed in connection with the apparatus. 165 The main cableway of the device is shown at 170 5, such main cable extending from the head 175 tree to a tail tree or support (not shown). 180

C is the carriage of the apparatus, and 7 is 185 an out-haul rope extending from the engine 190 drum b through the guide-sheave 8 at the 195 head tree and thence across the carriage to 200 the tail tree and back again, being secured at 205 9 to one side of the carriage. The skidding 210 rope 10 is operated by the drum b', such rope 215 extending over the sheave 11 at the head sup- 220 port and thence to the carriage.

12 is the slack pulling rope operated from 225 the drum b' of the engine, such rope also ex- 230 tends over a sheave 13 at the head tree and 235 thence to the carriage. The hoisting rope of 240 the apparatus is shown at 14 and carries at 245 one end the tongs 15. The main or carrying 250 cable 5 is connected with the main cable exten-

sion 16 at the point 17, such extension passing over the guide block 18 at the head support.

The skidding apparatus just described is of a well known construction, and the operation of the same will be readily understood.

In Fig. 1, the main cable extension 16 is connected at the point 17^a with a plurality of blocks and tackles D and E, each comprising a running block and a fixed block reeved together in the manner hereinafter described. For the purpose of convenience we will herein-after designate these blocks and tackles as heel blocks.

15 The block D is provided with an end loop 19, while the block E is provided with a similar loop 20, whereby such blocks may be detachably connected to any suitable anchorage, such as the stumps *f*. As stated, the 20 parts D and E are in the form of blocks, and for the purpose of applying tension, each is provided with a rope or line extending to drums mounted on the engine for this purpose. As will be seen from the drawings, the 25 block D has a tension rope 21 extending to a sheave or pulley 22 at the head tree, and thence to the drum *b*³ of the engine, while the block E is similarly provided with a rope 23 passing over the pulley 24 and thence to the drum *b*⁴ on the engine.

In Fig. 3, we have shown a construction of engine especially adapted for use in conjunction with the cableway of the character herein described. As stated, B indicates the engine as a whole, but in said figure the boiler, certain drums, and the connections therefor for operating the hoisting and hauling ropes are omitted, while additional drums *b*³ and *b*⁴ are provided. These drums are fast on 40 the shafts *b*⁵ and *b*⁶ each drum having a large gear wheel *b*⁷ adapted to mesh with a clutch pinion *b*⁸ loose upon the power shaft *b*⁹.

*b*¹⁰ indicates clutch members splined to the power shaft to turn therewith, but free to slide 45 or shift longitudinally of the shaft, and each of such members engages with the adjacent clutch member *b*⁸ to turn the latter with the shaft. Each of the drums *b*³ and *b*⁴ is provided with a band brake *b*¹¹ operated by a 50 foot-lever *b*¹² so that by applying its brake either of the drums may be held against revolution as desired. One of the end flanges of each drum is also equipped with a circular rack *b*¹³ adapted to be engaged by a suitable 55 pawl *b*¹⁴ to lock the drum against movement.

The operation of the apparatus is as follows: When it is desired to log a run, the parts are assembled substantially as shown in Fig. 1, the main cable-way 5 being held taut 60 by tension applied to the extension 16 through one of the heel blocks, in the present instance, that shown at D, the tension rope 21 being drawn taut by winding upon the drum *b*³ of the engine. In the meantime, the

running block E is slack and loose, and its 65 tension line is also necessarily loosened by reeling off from the drum *b*⁴. After the run has been logged, it is desirable to slacken tension rope 21 to permit the main cable 5 to be slackened and lowered so that it may be uncoupled and a second similar cable connected at the point 17 in place of the first one. This is accomplished by permitting the line 21 to slacken off the drum *b*³, said drum being released, and the cable in use is consequently 75 lowered. The second cable is then attached and the drum *b*⁴ is actuated to haul in the line 23 which tends to elevate the main cable and tighten or tension the heel block E. The block D which, as above recited, has been 80 loosened by releasing the drum *b*³ and permitting the line 21 to slacken, may then be removed from its stump and with its parts carried over past the now tensioned block E and secured to another stump or anchorage 85 opposite the next run.

In Fig. 2, we have shown a slightly modified form of device, for, in this case, instead of employing a single rope forming a main cable extension or guy, we employ a plurality of guy ropes 16^a and 16^b each of which passes over the guide-sheave 18; the ends of the guys being detachably connected to the main cableway at the point 17 in any suitable manner. The apparatus shown in Fig. 95 2 has the same mode of operation as that shown in Fig. 1, and such operation, therefore, need not be described in detail.

While we have herein shown and described one particular embodiment of our invention, we wish it to be understood that we do not confine ourselves to all the precise details of construction herein set forth, as there may be modifications and variations in certain respects without departing from the spirit of 100 the invention or sacrificing any of the advantages thereof.

Having thus described our invention, what we claim and desire to secure by Letters 105 Patent is:

1. In a conveying apparatus the combination of a support, a main cableway, a rope or guy connected to said main cableway, and a plurality of tension devices secured to said 110 guy and connected to suitable anchorages. 115

2. In a conveying apparatus the combination of a support, a cableway, a rope connected to said cableway, a plurality of tension devices connected to said rope, a drum for each of said tension devices, and an engine for operating said drums. 120

3. The combination of a support, a cableway connected to said support, a plurality of tension devices connected to said cableway being suitably anchored, and means for applying tension to one of said devices and removing such tension from another of said devices. 125

4. The combination with a cable, of means for maintaining tension upon the same comprising a plurality of running blocks connected to such cable, an anchorage for said blocks, and means for applying tension to and removing tension from each of said blocks at desired times.

5. The combination of a support, a cableway, a plurality of tension lines or ropes connected to said cableway, a running block for each of said ropes, and means for applying and removing tension from said blocks to tension or loosen its rope.

6. The combination of a support, a main cable, an extension rope connected to said cable and passing over a guide on said support, a plurality of lines connected to said cableway extension, a running block for each of said lines, a plurality of anchorages, means for detachably securing said blocks to the anchorages, and means for applying and removing tension from each of said blocks at desired times.

7. The combination of a support, a main cableway, a line connected to said cableway and passing over a guide on said support, a plurality of anchorages, a rope extending from each anchorage to the cable line, an engine for tensioning one of said ropes while the other rope is loosened.

8. In a conveying apparatus, the combination of a cableway, a plurality of tension lines for said cableway, and means for actuating

the tension lines, such means comprising a drum for each of said tension lines.

35

9. In a conveying apparatus, the combination of a main cableway, a guy for said cableway, a plurality of tension devices secured to said guy and connected with suitable anchorages and means for tensioning said devices, comprising an engine having a drum for each of said devices, a brake for each drum and a clutch mechanism between each drum and the power mechanism of the engine for transmitting motion to the drum.

40

45

10. The combination of a cableway, a plurality of tension devices therefor and mechanism for operating said tension devices comprising an engine having a plurality of drums, a power shaft, a clutch mechanism interposed between each drum and the shaft whereby each drum may be driven from the shaft, a brake for each drum, and mechanism for locking each drum against movement.
